UNITED STATES PATENT OFFICE

ALBERT F. FIFIELD, OF ST. CATHARINES, ONTARIO, CANADA, ASSIGNEE TO THE AMERICAN FORK & HOE COMPANY, OF CLEVELAND, OHIO, A CORPORATION OF OHIO

RAIL ANCHOR

Application filed September 16, 1929. Serial No. 392,869.

My invention relates to rail anchors and relates particularly to rail anchors of the type generally known as two piece anchors and which comprise a clamp element adapted to be driven onto one rail base flange and a retaining clip adapted to be interlocked therewith and to retain the clamp from displacement.

An object of my invention is to provide an improved rail anchor of the above character adapted for ready application to a rail base and ready removal therefrom, but which will not become dislodged by application of the stresses and shocks imparted thereto incidental to the use of the rails.

Another object of my invention is to provide an improved rail anchor, which may be inexpensively manufactured, but which will be highly efficient in use to prevent creeping of the rails to which it is attached.

Another object of my invention is to provide an improved two piece rail anchor comprising a clamp and clip, the clip being adapted to be removed and another clip of the same kind substituted but of a different size to accommodate rail bases of different sizes.

Another object of my invention is to provide an improved rail anchor which will strongly resist improper distortion incidental to the forces exerted upon it during use and yet which may be inexpensively manufactured largely or entirely of sheet metal.

Another object of my invention is to provide a rail anchor in which the forces imparted to a part of the anchor depending below the rail base tending to cant the anchor rotationally in a vertical plane will be strongly resisted, but will brace widely separated jaw portions of a clamp portion of the anchor.

Other objects of my invention and the invention itself will become apparent by reference to the following description of an embodiment thereof, and which embodiment is illustrated in the accompanying drawings.

Referring to the drawings, Fig. 1 illustrates in side elevation a rail anchor disclosing the principles of my invention shown as

attached to a rail base, which is illustrated in transverse section;

Fig. 2 is an end elevational view of an anchor attached to a rail shown in side elevation;

Fig. 3 is an inclined sectional view of the attached anchor taken on the line 3-3 of Fig. 1;

Fig. 4 is a longitudinal section view of the attached anchor taken on the line 4-4 of Fig. 2;

Fig. 5 is a perspective view of the clamp element employed in the said embodiment;

Fig. 6 is a rear elevational view of the clamp per se;

Fig. 7 is an elevational view of the clamp element employed in the said embodiment shown in normal form assumed when unattached.

Referring now to all of the figures of drawings and in all of which like parts are designated by like reference characters:

The rail base to which the anchor is to be attached is shown at 1 and comprises flanges 2 and 3. At 4 I show a fixed tie of the road bed supporting the rails, such as the rail 1, and adapted to be engaged by a portion of the rail anchor affixed to the rail to restrain creeping of the rail.

The rail anchor of the embodiment of my invention illustrated in the drawings comprises a clamp 5 and a separate clip 6, the clip 6 having a short upstanding hook 7 at its tip and its other end is reversely turned to form an open loop 8, the loop and hook projecting from the same side of the clip.

Fig. 7 illustrates in solid lines the normal form of the clip and in dotted lines the approximate form of the clip when distorted by being applied, jointly with the clamp 5 to a rail base; when applied the loop 8 is opened somewhat more widely than Fig. 7.

The clamp 5 is preferably in the form of a channel having a rear end wall 9 and side walls 10 and 11, the end wall being pierced to provide a longitudinally extending aperture 12, an inwardly projecting preferably arcuate tongue 13, being formed from the material otherwise disposed in the aperture during the piercing operation.

The channel is deformed at its upper end, being turned inwardly so as to cause the clamp to have a pendant channel portion and a clamping portion inturned with reference thereto at an acute angle and provided with a longitudinally extending medial depression 14 with longitudinal side ridges 15 and 16 to provide a pair of spaced jaws 17 adapted to over-lie the upper surface of a rail base flange such as 3, and a pair of lower jaws 18 extending obliquely inwardly to merge with the edges 19 of the channel sides 10 and 11 and adapted to under-lie and engage with the lower surface of the rail base flange such as 3.

The cooperating upper jaws 17 and lower jaws 18 are adapted to embrace the rail base flange 3 when the clamp is driven thereon by striking the clamp with a maul in the direction and approximately at the point indicated by the arrow 20 of Fig. 1.

The trough or depression 14 is provided with an end wall or stop 21, at the forward end of the upper arm of the clamp and extends rearwardly therefrom to the upper edge of the aperture 12 as defined by the inwardly projecting tongue 13. When the anchor is assembled for use on the rail, the forward end of the clip carrying the hook 7 is projected from the rear side of the anchor clamp through the aperture 12 of the rear wall 9 with hooks 7 and 8 extending upwardly and the forward edge 22 of the open hook 8 is placed within the groove or depression 14 on the upper surface of the clamp and between the longitudinally extending spaced ridges 15 and 16 formed thereon, which serve to guide the end 22 of the hook forwardly when the hook is driven tightly onto the clamp.

The clamp 5 is preferably driven onto its associated rail base flange 3 before the application of the clip 6, and when this procedure is adopted, the clip 6 is driven by the maul striking from and at approximately the point indicated by the arrow 20, as before and the engagement of the short arm 23 of the loop 8 with the upper surface of the groove 14 of the clamp will effect a tendency toward rotational movement of the hooked end 7 about the engaged depressed portion of the clamp, to force the hook 7 upwardly, pressing the reach arm 24 intermediate the loop and hook tightly against the bottom of the rail base and the energy stored in the resilient clip 6 as a result of this tendency toward rotational movement and the resiliency of the clip will finally, upon complete driving of the clip to the "home" position indicated in Fig. 1, will effect a snapping of the hook 7 over the edge of the rail base flange 2 to accomplish abutting engagement between the inner surface of the hook and the vertical edge surface of the rail flange. Engagement of the end edge 22 with the stop

21 immediately prior to the snapping of the shoulder 7 over the rail flange 2, prevents further movement of the free end of the hook 8 and consequently further driving to accomplish the snapping action results in deflection of the intermediate portion of the loop 8 and portions immediately adjacent thereto, to accomplish the slight additional longitudinal projection of the hook 7 over the edge of the base flange.

This yielding of the resilient loop portions is immediately followed by a retrectoral action tending to retract the hook 7 transversely of the rail base and being continuously resiliently effected along with the continuously resiliently effected upward pressure exerted upon the hooked end of the clip maintains a tight grip of the hook 7 against the vertical edge surface of the rail.

The inwardly turned tongue 13 integrally secured to the clamp 5 forms a projection of the depressed portion 14 of the clamp which is embraced by the clip hook 8 forming a seat for inner surface portions of the shorter and longer arms of the clip hook.

In operation, the anchor of my invention operates to grip the rail base flanges by what are commonly known in the art as sluing grip and canting grip actions effected by attempted creeping of the rail carrying the anchor to press that one of the lateral channel walls 10 and 11 next adjacent the tie 4 thereagainst.

A further creeping effort will be restrained upon a slight tilting effort effected upon the clamp by its lower channel portion engaging the tie and by a slight sluing effort effected thereupon by the same contact with the tie, whereby the clamp is slightly tilted and the clip is slightly slued to take a more oblique position relative to its initial position normal to the axis of the rail with the combined result that opposite jaw edges of the anchor clamp disposed at the two sides of the clamp, one engaging the upper surface of the rail base flange 3 and the other the lower surface thereof, will make a biting gripping contact therewith; also an inner edge of the inner surface of the hook 7 nearest the tie and a jaw portion of the clamp on the opposite side of the anchor will cooperate to effect the sluing grip.

The resiliently deformed clip effected during the driving on operation will effect maintenance of the anchor in the rail gripping position, which it adopts in service during use of the anchor on the rail to prevent relative creeping of the rail which carries the anchor.

Having thus described for purposes of illustrating my invention one embodiment thereof, I am aware that numerous and extensive departures may be made from the embodiment of my invention herein illustrated and described, but without departing from the spirit of my invention.

I claim:

1. A two piece rail anchor comprising a clamp having jaws adapted to grip a rail base flange when driven thereon and a pendant portion adapted to engage an abutting rail supporting tie, and a clip having a rail edge surface abutting hook at one end and an open loop at the other end, said clamp having a wall perforated below its jaws, said clip adapted to be extended through the clamp perforation with its hook and loop upper-most, and said hook foremost, said loop adapted to resiliently contractingly embrace both said jaws, said hook adapted to engage the vertical side edge of the opposite rail base flange and to be snapped into engagement therewith upon driving of the loop onto the clamp jaws.

2. A two piece rail anchor comprising a clamp having jaws adapted to grip a rail base flange when driven thereon and a pendant portion adapted to engage an abutting rail supporting tie, and a clip having a rail edge surface abutting hook at one end and an open loop at the other end, said clamp having a wall perforated below its jaws, said clip adapted to be extended through the clamp perforation with its hook and loop upper-most, and said hook foremost, said loop adapted to resiliently contractingly embrace both said jaws, said hook adapted to engage the vertical side edge of the opposite rail base flange and to be snapped into engagement therewith upon driving of the loop onto the clamp jaws.

3. A two piece rail anchor comprising a clamp having jaws adapted to grip a rail base flange when driven thereon and a pendant portion adapted to engage an abutting rail supporting tie, and a clip having a rail edge surface abutting hook at one end and an open loop at the other end, said clamp having a wall perforated below its jaws, said clip adapted to be extended through the clamp perforation with its hook and loop upper-most, and said hook foremost, said loop adapted to resiliently contractingly embrace both said jaws, said hook adapted to engage the vertical side edge of the opposite rail base flange and to be snapped into engagement therewith upon driving of the loop onto the clamp jaws, said clamp comprising a stop engageable with the forward edge of the free arm of the loop when said loop is driven onto the clamp jaw.

4. A two piece rail anchor comprising a clamp having jaws adapted to grip a rail base flange when driven thereon and a pendant portion adapted to engage an abutting rail supporting tie, and a clip having a rail edge surface abutting hook at one end and an open loop at the other end, said clamp having a wall perforated below its jaws, said clip adapted to be extended through the clamp perforation with its hook and loop upper-most, and said hook foremost, said loop adapted to resiliently contractingly embrace both said jaws, said hook adapted to engage the vertical side edge of the opposite rail base flange and to be snapped into engagement therewith upon driving of the loop onto the clamp jaws, said clamp pendant portion being of generally channel form and comprising a rear wall portion having said perforation.

5. A two piece rail anchor comprising a clamp having jaws adapted to grip a rail base flange when driven thereon and a pendant portion adapted to engage an abutting rail supporting tie, and a clip having a rail edge surface abutting hook at one end and an open loop at the other end, said clamp having a wall perforated below its jaws, said clip adapted to be extended through the clamp perforation with its hook and loop upper-most, and said hook foremost, said loop adapted to resiliently contractingly embrace both said jaws, said hook adapted to engage the vertical side edge of the opposite rail base flange and to be snapped into engagement therewith upon driving of the loop onto the clamp jaws, said clamp pendant portion being of generally channel form and comprising a rear wall portion having said perforation, said clamp formed with a longitudinally extending intermediate portion, depressed inwardly relative to laterally disposed ridge portions positioned on the upper part of the clamp, said loop being adapted for position on said depressed portion intermediate the ridges.

6. A two piece rail anchor comprising a resilient reach arm adapted to be projected below a rail base transversely thereof and terminating at one end in a loop, and at its other end in a hook, engageable with a lateral surface of a rail base flange and a clamp element having a portion embraced by said loop and having a pair of upper and lower rail base engaging jaws adapted to grip the other rail base flange when driven thereon and a portion pendant therefrom for engagement with a lateral surface of a rail supporting tie.

7. A two piece rail anchor comprising a resilient reach arm adapted to be projected below a rail base transversely thereof and terminating at one end in a loop, and at its other end in a hook, engageable with a lateral surface of a rail base flange and a clamp element having a portion embraced by said loop and having a pair of upper and lower rail base engaging jaws adapted to grip the other rail base flange when driven thereon and a portion pendant therefrom for engagement with a lateral surface of a rail supporting tie, said reach arm projected through a wall of said pendant portion and adapted for resilient distortion tending to continuously effect an upward tilting effort upon its hooked end to maintain the hooked end in engagement with the bottom surface of the rail base and resiliently distorted during the driving in its loop portion to longitudinally extend the hook over the rail base flange edge, to said up resilient retractoral effort therein constantly exerting a resilient effort to press the hook against the lateral surface of the said rail base flange.

8. A two-piece rail anchor comprising a trough shape clamp bent intermediate its ends to form opposing rail base flange enveloping jaws and pierced below the jaws, and a resilient clip formed with a resilient loop at one end and a tongue extending from an arm of the loop through the pierced clamp below

the rail base, said loop embracing the jawed portion of the clamp, said tongue underlying the rail base and provided with an upturned free end portion adapted to be snapped over 5 the remote rail base flange edge, when the clip is driven onto the clamp and with the tongue projected through the pierced clamp.

8. In a rail anchor, a clamp element in the form of a sheet metal channel bent intermediate its ends to provide a pair of channeled arms disposed relatively at an acute angle to each other, with their channeled sides disposed innermost, and providing rail flange engaging jaws by the opposing edges of their 15 lateral walls, and a reach arm element engageable by an end with said clamp adapted to be projected below a rail base and to make resiliently mounted engagement with a lateral surface of the opposite rail base flange 20 by its other end, said reach arm element retaining said clamp on its associated rail base flange.

9. In a rail anchor, a clamp element in the form of a sheet metal channel bent intermediate its ends to provide a pair of channeled arms disposed relatively at an acute angle to each other, with their channeled sides disposed innermost, and providing rail flange engaging jaws by the opposing edges of their 30 lateral walls, and a reach arm element engageable by an end with said clamp adapted to be projected below a rail base and to make resiliently mounted engagement with a lateral surface of the opposite rail base flange 35 by its other end, said reach arm element retaining said clamp on its associated rail base flange, one of said clamp arms disposed pendantly below its associated rail base flange and having a pierced wall, said reach arm element projecting through the opening provided by the pierced wall. 40

In testimony whereof I hereunto affix my signature this 30th day of August, 1929.

ALBERT F. FIFIELD.
